B. BOYKIN, JR

FRICITION MAKE UP POST

Filed May 20, 1924

BURWELL BOYKIN JR. Inventor

By *Jesse R. Stone*

his Attorney

UNITED STATES PATENT OFFICE.

BURWELL BOYKIN, JR., OF BEAUMONT, TEXAS.

FRICTION MAKE-UP POST.

Application filed May 20, 1924. Serial No. 714,556.

To all whom it may concern:

Be it known that I, BURWELL BOYKIN, Jr., a citizen of the United States, residing at Beaumont, Texas, have invented a certain 5 new and useful Improvement in Friction Make-Up Posts, of which the following is a specification.

My invention relates to a make-up post to be employed on rotaries in drilling operations for oil, water, sulphur and the like. 10 It is adapted to provide a stop for the handle of the wrench employed in unscrewing the joints of the pipe while the said pipe is being introduced into the well.

15 It is now customary, in screwing up the joints of pipe such as drill stem while it is being introduced into the well, to hold the pipe in the center table of the rotary in a stationary position and to rotate the joint 20 or coupling constituting the upper half of the tool joint by means of a wrench engaging the tool joint and having the handle thereof bearing against a make-up post secured in an outer rotary portion of the table. 25 In this way the wrench is swung around and around the pipe until the tool joint is screwed up firmly.

It is an object of my invention to provide a make-up post to be employed on rotaries 30 which will release the handle of the wrench when the joint has been fully screwed up, thus avoiding jamming the threads of the joint so firmly together as to lock the joint unnecessarily tight.

35 It is another object to provide a stop member of the make-up post against which the handle of the wrench may bear, which is held frictionally against rotation by a predetermined pressure and which will release the wrench handle when this pressure has been exceeded.

40 It is also desired to form a plurality of stop fingers, so that when the wrench handle has once been released, another stop finger will be forced into operative position so as to again engage the wrench handle when desired. Other objects and advantages of the device will be apparent from the description which follows:

45 In the drawing herewith a preferred embodiment of the invention is disclosed. Fig. 1 is a side elevation of the make-up post, the upper end thereof being in central section on the line 1-1 of Fig. 2, the upper and lower 50 ends being seen in the direction of the

arrows. Fig. 2 is a front elevation of the device. Like numerals of reference refer to like parts in both the views.

The lower portion of my make-up post is cylindrical as shown at 1, and the lower end 60 is reduced somewhat in diameter at 2 to fit within a socket ordinarily provided within the rotary table. A laterally projecting bracket 3 on said post is held in position thereon by set screw 4. Said bracket has a 65 downwardly extending angular lug 5 which is adapted to engage with a stop lug upon the table and thus prevent rotation of the post.

The upper end of the post is flattened and 70 formed into a head 6 which is cylindrical in general outline. A central opening is made through said head to receive a clamping bolt 7. Below the head, the body of the post is 75 flattened for a short distance to allow the rotation of the stop discs, as shown particularly in Fig. 1.

Fitting against the opposite sides of the head are two discs 8 and 9, which are rotatable upon the shaft 7. Said shaft may be 80 a bolt of suitable size having a nut 10 on one end thereof. The disc 8 is recessed 85 slightly at 11 to receive the head 12 of the bolt. Said disc is also recessed on its inner face to receive an annular friction member 13, which may be of wood or some composition adapted to frictionally engage the head 6 of the post; said ring 13 is held in position in its annular seat by means of bolts or pins 14. Each of the discs has 90 radially projecting stop fingers 15. As shown particularly in Fig. 2, these stop fingers have a flat face presented in the direction to receive the handle of the wrench. The other side of the finger is formed with a 95 downwardly inclined rib 16, to reinforce and strengthen the supporting finger. I provide a plurality of these stop fingers and in the present embodiment I have shown six such members.

The disc 9 has a central hub 17 which has a cup shaped outer recess 18 to receive a spring 19. Said spring bears at its inner end against the wall of the disc, and at its outer end bears against a washer beneath the nut 10. It thus acts to resiliently press the discs inwardly toward the head to maintain a frictional contact therewith. An annular recess on the inner face of the disc 9 forms a seat for a second ring 13 110

similar to that employed on the opposite disc. The hub 17 of this disc is extended inwardly to fit within a recess 19 in the face of the head. It has slight movement there-
5 in against the tension of the spring 18.

In the use of this device the post is se-
cured in proper position upon the outer ro-
tary table, and when the wrench has been
engaged upon a pipe coupling or tool joint,
10 it is in such position as to bear against the
face of the upper stop finger 15. The ro-
tation of the table will then carry the post
1 and the handle of the wrench around the
pipe, thus tending to screw up the joint.
15 When the joint has been screwed as tight as
is desired, the pressure of the handle of the
wrench upon the stop finger will cause the
discs to rotate, thus releasing the handle
20 of the wrench and bringing the next adja-
cent stop finger into operative position. It
is contemplated that the necessary friction to
hold the wrench may be adjusted by the ten-
sion of the nut 10 upon the spring, so that
25 the wrench handle will be released at the
time when the joint is sufficiently tight.
Danger of locking the threads of the joint
or mutilating them in any way will be thus
avoided. It will then be possible to unscrew
30 the joints of the pipe more readily when
it becomes desirable to remove the drill
stem from the well.

It will be noted that the action of this
make-up post is entirely automatic in its
releasing of the wrench handle at the prop-
er time, and that the post is in prop-
35 er position for use without readjustment
whenever needed. It is possible to produce
the proper friction between the discs and
the head of the post without the necessity
40 of the spring, and I do not wish to be
limited to the exact type of friction device
employed, as various modifications thereof
may be made coming within the scope of
the invention.

What I claim as new, and desire to pro- 45
tect by Letters Patent is:

1. A make-up post comprising an upright
supporting post, a flattened head on the
upper end thereof, a rotatable disc on each
50 face of said head, radial stop fingers on
said disc, and means to resist the rotation
of said disc with a predetermined force.

2. A make-up post comprising an upright
supporting post, a head thereon, a rotatable
disc on said head, radially extending fingers 55
on said disc, and means to resist the rota-
tion of said disc with a predetermined force.

3. A make-up post comprising an upright
supporting post, a head on the upper end
thereof opposite rotatable discs on said head,
60 each disc having outward extending stop
fingers thereon, and resilient means to re-
sist the rotation of said disc for the purpose
described.

4. A make-up post comprising an upright 65
supporting post, a flattened head thereon, a
disc pivoted for rotation on said head, means
on said disc to engage a wrench handle, a
friction ring between said disc and said
head, and means to hold said friction ring 70
against said head with a predetermined
pressure.

5. A make-up post comprising an upright
supporting post, a flattened head thereon,
opposite rotatable discs on said head, radi- 75
ally extending means on said discs to en-
gage a wrench handle, friction means on
said discs and resilient means to hold said
friction means in contact with said head
for the purpose described.

6. A make-up post comprising an upright
supporting post, a head thereon, and a stop
member held frictionally against said head
with a predetermined force.

In testimony whereof I hereunto affix my 85
signature this 16th day of May A. D. 1924.

BURWELL BOYKIN, JR.
